COMBINED WALL SHELF AND PLANTER

George Matthay, Chicago, Ill.

Application February 24, 1958, Serial No. 49,769

Term of patent 14 years

(Cl. D33—3)

Fig. 1 is a front elevational view of my design for a combined wall shelf and planter;

Fig. 2 is a top plan view thereof; and

Fig. 3 is a side elevational view.

The dominant features of the design reside in the portions shown in full lines on the drawing.

I claim:

The ornamental design for a combined wall shelf and planter, substantially as shown and described.
